UNITED STATES PATENT OFFICE.

WALTER S. SUTTON, OF KANSAS CITY, KANSAS.

HOISTING APPARATUS FOR DEEP WELLS.

No. 850,549.

Specification of Letters Patent.

Patented April 16, 1907.

Application filed August 26, 1905. Serial No. 275,889.

To all whom it may concern:

Be it known that I, WALTER S. SUTTON, a citizen of the United States of America, residing at Kansas City, in the county of Wyandotte and State of Kansas, have invented certain new and useful Improvements in Hoisting Apparatus for Deep Wells; and I do hereby declare that the following is a full, clear, and exact description of the invention, such as will enable others to make and use the same, reference being had to the accompanying drawings, forming a part of this specification.

In the ordinary well-pumps in use the influx of sand, which clogs the pump-valves, and more especially the sand from oil-bearing strata of deep oil-wells, necessitates the frequent withdrawal of the sectional pump-rods employed and by slow manual labor when the power has ceased to operate the pump. The fine sand almost invariably pumped in small quantities with the oil from oil-wells wears out the packing of the working plunger, and the consequent raising and dismemberment of the rods for the purpose of removing the plunger for the renewal of the packing occasions long delays and is a constant source of expense.

To accomplish the withdrawal of the plunger and valves from the pump-tube with greater rapidity and to utilize therefor the same power used for pumping is the principal object of the invention.

Secondly, the invention has for its object the transmission of the power for actuating pumps from reciprocating pump-energizing means to raising and lowering mechanism; third, to provide for an accelerated downward movement of the working parts of the pump in the pump-tubing to the pump-barrel.

The invention consists in the novel construction and combination of parts, such as will be first fully described, and specifically pointed out in the claims.

In the drawings, Figure 1 is a sectional view of a drilled well, showing a portion of the well-casing, the pump-tube and barrel, the pumping-jack frame, and the power-operated reciprocating devices actuating the frame, the derrick, and novel hoisting mechanism for the pumping-cable in power communication with the pumping-jack frame, and the means for controlling the movement of the hoisting mechanism. Fig. 2 is a detail view in perspective, upon an enlarged scale,

of the pumping-jack frame and its support, the reciprocating stirrup, the derrick, the upper portion being shown broken from the lower portion, the compound cable-hoisting wheel or drum, and ratchet on the support for the pumping-jack frame, the brake-band, the pawls, the means for operating one pawl and brake-band simultaneously and for automatically arresting the movement of the hoisting-wheel. Fig. 3 is a vertical sectional view taken through the winding wheel or drum, showing broken portions of the wheel-supports and of the pumping-jack frame. Fig. 4 is an enlarged detail vertical sectional view of the upper portion of the well-casing, showing a portion of the well-pump tube, the discharge-opening, the antifriction guide-tube and cable, the suspended cradle and the clamping-plates and cable attachments. Fig. 5 is an enlarged vertical section of the drilled well, showing also an enlarged view of the pump-tube and smaller pump-barrel, the working plunger and valve, and the stationary-valve casing and stem telescopically connected with the working plunger. Fig. 6 is a detail view of the sinker, showing the cable-connecting link for connecting the cable therewith and sectional parts of the sinker. Fig. 7 is a detail view in perspective of the brake-band-connecting-link, and pawl, showing the concentric pawl and link carrying and binding sleeves on the transverse rod on the supporting-frame.

Similar numerals of reference indicate corresponding parts in all the figures of the drawings.

Referring to the drawings, 10 indicates the vertical well-opening extending below the surface of the ground the requisite depth, and 12 the well-casing, which is shown extended downwardly the usual distance in the well. The upper end of the well-casing extends a short distance above the surface of the ground and is externally screw-threaded, and upon said end is fitted an internally-screw-threaded casing-head 14. In the upper portion of the casing-head 14 is an opening 15 of smaller dimensions than the casing 12, and upon the upper surface of the casing-head, extending around said opening, is an annular detachable ring 16. Through the opening 15 extends the upper end of the pump-tube 17, which is externally screw-threaded, and upon said end is fitted the upper coupling 18 of said tubing, which bears upon the ring 16. Upon the casing-head is

fastened a pair of clamps 19, which support the front legs 57, of the jack-frame, and through the ends of which plates extend the bolts 20, upon which bolts are the binding-sleeves 19^x.

In the upper coupling 18 of the well-tubing is a screw-threaded nipple 21, and connected with the upper end of the nipple is a T-coupling 22. In the side outlet 23 of the T-coupling 22 is a nipple 24, forming a discharge-tube for the fluid. With the upper end of the T-coupling 22 is connected the screw-threaded end 25 of the stuffing-box 27, and through the opening 28 in the cap 26 of the stuffing-box 27 extends the non-friction guide-tube 29, which works fluid-tight in the stuffing-box.

At the lower end of the pump-tube 17 is the pump-barrel 30, which extends downwardly nearly to the bottom of the well, as seen in Figs. 1 and 5, and is slightly smaller in its interior diameter than the pump-tube 17, the upper externally-screw-threaded end of the pump-barrel being connected with the lower screw-threaded end of the tube by the reducing-coupling 17^x. In the lower end of the pump-barrel is an opening for the fluid, the sides of which are drawn inwardly in a slight degree to form a seat 31 for the valve-casing 32.

32 indicates the normally stationary valve-casing for the valve 33, which casing is seated during the operation of the pump on the seat 31, the valve being located in the cage or chamber 34 in the casing. From the valve-chamber extends downwardly a short tube 36, around which is the packing 37, below which packing the tube is externally screw-threaded and bears an internally-screw-threaded nut 38, which conforms to and rests in the seat 31.

40 With the upper end of the valve-casing 32 is connected the lower end of a short connecting rod or stem 39, above which rod or stem is a working plunger, consisting of a hollow pipe 40, of considerable length, the circumference of which is slightly less than the inner circumference of the pump-barrel 30. A portion of the lower end of the plunger or pipe 40 is externally reduced in size and provided with a packing 41. Below the packing the

50 pipe is externally screw-threaded and a nut 42 secured thereto. Connected with the nut is a cup-shaped hanger 43, having side openings 44 and a vertical opening 45, through which latter opening and end of pipe 40 extends for a short distance the upper end of the valve-stem 39. Upon the upper end of said stem is an enlargement or head 46, the distance of said head above the hanger 43 being sufficient to permit the reciprocal pumping movement of the plunger without contact with the hanger. The upper end of the plunger 40 is closed by a crown 47, and upon the upper surface of the crown is a pin 48.

Within the pipe or plunger 40 beneath the 65 crown the walls of the pipe are hollowed out

for a short distance, downwardly to form a valve-chamber 49, in which chamber is a ball-valve 50. In the sides of the pipe 40, leading to the chamber 49, are vertical openings 51, through which the fluid passes to the pump-tube.

With the pin 48, on the crown 47, of the working plunger, is connected the joint 52 of a sinker 53, of suitable length and requisite weight. The sinker is made in sectional parts, each part being provided with a screw-joint 52^x and each section having at each end close to the joint a square portion 53^x for the engagement of a wrench for connecting and disconnecting the sectional parts. 80 This sinker is made in circumference as large as is compatible with the free upward passage of the fluid pumped between it and the walls of the tubing and is of a length proper to give the necessary weight to depress the 85 working plunger and retain the pumping-cable taut in the downstroke of the pumping-jack.

Upon the upper end of the sinker 52 is a 90 rope-socket 54, within which socket is fastened the lower end of the pumping-cable 55, the upper end of which cable extends through the antifriction guide-tube 29 in the pump-head, thence upwardly above the said tube, and is operated as further described.

Upon the surface of the ground adjacent to the well-casing 12 is an upright stationary frame, comprising parallel side bars or legs 57, the lower ends of which bars are secured to the ends of the bolts 20 on the outer side 100 of the clamping-plates 19 on the well-casing head 14 by the nut 20^x. A short distance away from the well-casing is located a heel-post 60, securely set in the ground. A bolt 61 is secured and transversely to the upper 105 end of the heel-post and held in place by means of a cap-plate 62 on the post. With the ends of the bolt are secured the lower ends of the rear converging angle-bars or legs 64 of the stationary frame. The upper ends 110 of bars 57 and also the upper ends of bars 64 are inclined toward each other, and through said ends extends a bolt 65, upon which are the nuts 66 and a binding-sleeve 67. (See Fig. 3.) Extending around said 115 binding-sleeve 67 is a concentric tube or journal 68, which is slightly shorter than the binding-sleeve. Upon the tube or journal 68 at a point equidistant from the bars 57 is securely clamped the split hub 69^x of a cable-winding drum or wheel 69. The periphery of wheel 69 is grooved or chambered concentrically to and between the sides, as at 70, and upon the periphery of one side of the drum or wheel are ratchet-teeth 71, and upon the periphery of the other side is a V-shaped 120 groove 72.

73 indicates a lifting or pumping jack of the ordinary construction and which is composed of parallel horizontally-extended bars 130

74, the inner ends of which bars are bolted or riveted at 75 to radial arms 76, which arms are connected with the trunnions 77, said trunnions being loosely mounted on the 5 journal 68 and upon each side of hub 69^x of the hoisting-wheel 69.

From the trunnions 77 extend downwardly radial arms 78, as seen in Fig. 3, and to said arms are bolted the upper ends of the downwardly-extended bars 79, which are slightly shorter than the horizontal bars 74. The outer surfaces and lower ends of the bars 79 are connected to the lower ends of the back brace-bars 80 by means of the bolt 81, extending through said bars, upon which is a nut 82. Upon the bolt 81, between the bars 128, is a binding-sleeve 83. The upper ends of the bars 80 are bolted to the outer surface of the bars 74 at a point a short distance inwardly 20 from the outer ends of said bars 74, which outer ends extend a short distance beyond a vertical line extending through the anti-friction guide-tube 29, through which the pumping-cable passes. Through said outer 25 ends of the bars 74 extends a bolt 84, upon which is a nut 85. Through the bars 74, immediately in rear of the upper ends of the brace-bars 81, extends a bolt 86, upon which is a nut 87. With the said bolts 86 and 84 30 are connected the upper ends of a pair of hangers 88, and with the lower ends of said hangers are pivotally connected the opposite ends of the suspended cradle 89, said ends being slotted, as at 90, (see Fig. 4,) and through 35 which ends pass transversely the pivots 91. Above the cradle and extending around the wire cable 55 is a head 92 for the antifriction guide-tube 29, having a circumferentially reduced or tapering lower end. In the cradle 40 is a vertical opening 93, within which opening the tapering lower end of the head 92 extends. In said lower end of the head is a screw-threaded socket 94, in which socket is secured the externally-screwed 45 threaded upper end of the polished tube 29. Upon the outer surface and lower end of the head 92 are the oppositely-extended trunnions 95, which rest in the grooves 96 in the cradle.

50 Upon the cable 55 above the head 92 to the polished tube 29 are the separate cable-clamping plates 97, secured together by the bolts 98. In the upper end of the head 92 is an annular recess 99, in which is a yielding packing 100. Extending around the cable 55 and within the recess 99 is a short follower or gland 101, which bears the weight of the clamps 97.

Upon the bolt 86, supporting one of the 60 cradle-hangers 88, is pivotally mounted a pawl 102, which engages with the ratchet-teeth 71 on the hoisting-wheel 69. Upon the bolt 84 is pivotally mounted a radial arm 103, upon the upper end of which arm is an 65 enlargement or weight 104, with which

weight is rigidly connected the stem of the forked arms 105, the forked portions of which arm extend in the direction of the hoisting-wheel 69.

With the radial arm 103 is pivotally connected one end of a rod 106, the other end of which rod is pivotally connected with the side portion of the pawl 102.

Extending through the bars 57 of the main supporting-frame for the pumping-jack and hoisting-wheel at a point at about midway 75 the ends of said bars is a transverse bolt 107, upon which is a nut 108, and a short distance from said bolt in the direction of the upper ends of the bars and adjacent to the 80 hoisting-wheel 69 is a similar transverse bolt 109, upon which is a binding-sleeve 109^x between bars 57 of said main frame. Upon the binding-sleeve is a loose-fitting outer sleeve 109^x, which is slightly shorter than the binding-sleeve. (See Fig. 7.) Connected with the sleeve 109^x is a radial arm 110, secured thereto by the binding-screws 112. Upon the same outer sleeve 109^x is a pawl 114, engaging with the ratchet-teeth 71 on the 85 hoisting-wheel, which pawl is secured to the sleeve by the binding-screw 115. To the outer surface of the pawl 114 is bolted the lower end of an operating-lever 116, which lever is bent at 116^x outwardly at right angles, so as to extend outside of the jack-frame and from said bent portion extended upwardly the requisite distance. When the pawl is in engagement with the ratchet-teeth 71, the lever, which is of considerable weight, 90 inclines backward, thereby holding the pawl in position, the radial arm 110 extending forwardly at an angle to the pawl. With the outer end of the arm 110 is pivotally connected a link 117, and with said link is connected 95 one end of a brake-band 118, which extends around the hoisting-wheel, and upon the inner surfaces of the band are V-shaped friction-blocks 119, formed in the arc of a circle, and which blocks are spaced apart on the 100 band and fit within the groove 72 in the periphery of the hoisting-wheel 69, giving rise to friction between said blocks and the grooved periphery of the wheel, the amount of which friction is regulated by the position 105 of the lever 116. The other end of the brake-band is secured to the rod 107 on the bars 57 of the main supporting-frame.

120 indicates a derrick, which is composed of a foot-beam 121, anchored to the ground by the post 122. Said foot-beam is located upon the side of the well-casing 12 opposite to that occupied by the main supporting-frame for the hoisting-wheel 69 and the jack-frame and a short distance from said well-casing. 125 With the foot-beam are connected the lower ends of the derrick-beams 123, the upper ends of which beams extend a considerable distance in height and are inclined laterally, and between the said upper ends is a sheave 130

124, journaled in the journal-boxes 125 on the outer surface of the beams. These beams are also inclined backwardly in position, so that the grooved surface of the front side of the sheave 124 will come into a position in a vertical line with the center of the pump-tubing. With the sides of the beams 123 are connected the upper ends of the angle-bars 126, the lower ends of which bars extend downwardly to the main supporting-frame for the hoisting-wheel and jack-frame and are connected with the bolt 65, supporting the wheel 69 axially and between the nuts 66 on said bolt and the upper ends of the bars 64 of said main frame. The weight of the bars of the derrick prevent the raising of the wheel-supporting frame. The upper end of the wire pumping-cable 55 is extended upwardly in the recess between the horizontal bars 74 of the jack-frame and the transverse bolts 85 and 86, connecting said bars thence upwardly over the sheave 124, thence downwardly within the recess 70 of the hoisting-wheel 69, in which it is secured and wound in coils.

127 indicates a reciprocating stirrup operating the pumping-jack frame, comprising the horizontally-extended parallel bars 128, which is located above the casing-head 14, the rear ends of which bars are pivotally connected with the transverse bolt 81 on the lower ends of the bars 79 of the jack-frame. The rear ends of the bars 128 on each side of the discharging-pipe 24, leading from the well-tubing, are connected anteriorly by a transverse curved bar. With the curved bar is connected one end of a power-operated rod or cable 131, the other end of which rod or cable is connected with an engine (not shown) transmitting a reciprocating motion to the stirrup in the usual manner and thence to the pumping-jack frame.

A considerable distance behind the heel-post 60 is a post 132, securely set in the ground. Pivotally connected at its inner end to the side and upper end of the post 132 is a rearwardly-extended support or beam 133, from the inner end of which beam extends upwardly a short distance and at right angles to beam 133 an arm 135, forming a vibrating support for the weight 136 on the beam 133, said beam being reinforced by a brace 137, extending from beam 133 to the arm or lever 135. With the upper end of said arm or lever 135 is connected one end of a short cable 138, upon the other end of which cable is a link 139, which link is connected with a transverse bolt 140, extending through the lower ends of the downwardly-extended bars 79 of the pumping-jack frame, which bolt is provided with a nut 141 and is located a short distance above the connecting-bolt 81 for said bars 79 and brace-bars 80.

In the operation of pumping, the pawl 102 is disengaged from the ratchet on the hoist-

ing-wheel 69, the forked arm 105 and the weight 103 being inclined or canted forwardly past a vertical line through the center of the supporting-bolt 84 into the position shown in full lines in Figs. 1 and 2. The pawl 114 is permitted to engage with the ratchet-teeth 71 on the hoisting-wheel, the operating-lever 116 being in a rearwardly-inclined position, as shown in full lines in Figs. 1 and 2, the brake-band 118 being loose upon the hoisting-wheel.

For the purpose of pumping, the cable 138, connected with the weighted vibrating beam 133, may be disengaged from the pumping-jack frame, its office being to cause a return movement of the pumping-jack frame when the cable 55, with its attached sinker or plunger, is being hoisted from the well. The position of the working plunger being within the pump-barrel 30 and the valve-casing 32 being on the seat 31 in the lower end of the pump-barrel, power is communicated to the stirrup 127 through the rod or cable 131 to communicate a horizontal reciprocating motion to the stirrup, and this motion is converted into a rotary movement of the lifting-jack frame, which results in a vertical reciprocating motion of the suspended cradle 89. This motion is communicated unchanged to the head 92 of the antifriction guide-tube 29, thence through the follower 101 to the clamping-plates 97, thence to the cable 55, the hoisting-wheel 69 being at rest. The upward movement of the pumping-cable 55 results in a corresponding upward movement of the sinker 53 and of the working plunger 40, the valve 33 in the valve-casing 32 lifting to admit the fluid into the pump-barrel 30, resulting in a uniform flow of the fluid through the lower valve. In the return movement of the plunger 40, which is accomplished by the weight of the sinker 53, the valve 33 in the valve-casing 32 closes, and the fluid is prevented from escaping from the pump-barrel and passes through the hollow plunger 40, through the upper valve-chamber 51, into the well-tubing above the plunger, the valve 50 in the chamber being lifted by the liquid, this liquid passing up the tubing and is discharged from the discharge-pipe 24. The packing 100 aids to prevent the loss of the fluid between the cable and the walls of the tube 29. The weight of the clamps, cable, sinker, and working plunger upon the gland 101 so flattens the rubber packing 100 as to cause it to expand laterally and pack off fluid-tight all space between the cable and the walls of the recess 99.

When it is desired to withdraw the working plunger and valve-casing from the well-tube, the cable 138 is connected with the vibrating weighted beam 133, the pawl 114 remains engaged with the ratchet-teeth 71 on the hoisting-wheel, and the weighted pressure-arm 103 is thrown backward into the

position as seen in dotted lines in Fig. 2, which action throws the pawl 102 into engagement with the ratchet-teeth 71 on the hoisting-wheel, the two forks of the arm 105 being in a nearly horizontal position, one in each side of the hoisting-cable 55 and vertically above the clamping-plates 97 on the hoisting-cable, which clamping-plates are now loosened from their grasp on the cable by the loosening of the nuts 98 on the clamping-bolts. The reciprocating movement of the stirrup and pumping-frame is then communicated to the hoisting-wheel 69 to cause an intermittent rotary movement of said wheel, thereby winding the cable 55 in the recess 70 of the wheel, and the plunger 40 is drawn out of the pump-barrel. As the head 46 on the stem 39 to the valve-casing 32 strikes the hanger 43 the casing is withdrawn from the seat and follows the plunger upwardly into the pump-tube. In this movement of the plunger the lower pawl 114 on the supporting-frame acts alternately to the upper pawl 102 on the moving jack-frame to hold the wheel as the said upper pawl releases its hold in the downward movement of the pumping-jack frame. The slack in the power-communicating cable or rod 131 in the above movement is taken up by the weighted beam 133. The rotary movement of the hoisting-wheel 69 is continued until the rope-socket 54, connecting the cable with the sinker 53, strikes the lower end of the polished or non-friction tube 29 and raises said tube with its head 92 out of the cradle 89, and with said head 92 the loose clamping-plates 97 until said clamping-plates attain a position above the lowest point reached by the forked arm 105 in the downward stroke of the jack-frame. On the next downstroke of the jack-frame the forked arm 105 on the weight 104 strikes the clamping-plates 97, causing the weighted arm 103 to be canted forwardly on the bolt 85 to such a degree that the center of gravity of said arm 103, with the attached forked arm 105, is in a position forward of a vertical line passing through the bolt 84. This movement is communicated, by means of the connecting-rod 106, to the pawl 102, disengaging the same from the ratchet-teeth 71, and the rotary action of the hoisting-wheel 69 is automatically stopped. In order that the sinker 53 and the plunger-valve casing and valves may be entirely removed from the well-tube, the stuffing-box 26 is removed from the upper end of the well-tube or the T-coupling 25 thereon. The pawl 102 is again thrown into engagement with the ratchet-teeth 71 on the hoisting-wheel and permitted to be so engaged until the sinker-working plunger and valve-casing for the lower valve are drawn from the well-tube, in which position the working parts enumerated are supported by the derrick 65 and in position for removal or repair. The pawl 102 is then disengaged from the hoisting-wheel by hand, the wheel being held by the pawl 114 from movement. When the plunger and sinker, with the valve-casing, are lowered again into the pump-tube and thence to the pump-barrel 40, the pawl 102 is disengaged from the ratchet-teeth in wheel 69. The brake-lever 116 is inclined forwardly, disengaging the pawl 114 from the wheel, and at the same time tightening the clutch of the band-brake upon the brake-groove 72 by the forward and downward partial rotation of the band-operating arm 110 and the working plunger and the sinker and valve-casing descend into the well-tube and barrel under perfect control. It is to be observed that the rotation of the pawl 114 with the brake-arm 110 prevents an accidental engagement of the pawl 114 with the ratchet-teeth on the wheel 69 during the reverse rotary movement of the wheel when the cable, plunger, and sinker are being lowered into the tubing under control of the brake.

In case a well produces oil having so much fine sand that there is sufficient in the twelve hundred feet column or more of oil left standing in the pump-tube at the cessation of pumping to form two or three feet of solid sand at the bottom in settling the plunger will be prevented from movement by the sand, and ordinarily the tubing and pump-rods are required to be drawn out of the well, an operation of much expense. When my invention is used in such wells, the accumulation of solid sand over the valves during inaction may be prevented by simply throwing into engagement the upper pawl and winding up sufficient length of the cable to withdraw both the working plunger and the standing valve from the working barrel into the larger tubing. This will allow the greater part of the fluid to settle back into the well, and the sand from whatever fluid remaining is enabled to settle past the plunger into the well.

The invention is applicable to various uses for communicating reciprocating movement to rotary hoisting mechanism and may be used in shafts of mines and like purposes, the leverage upon the circumference of the wheel 69 affording an increase of power to the lifting-jack frame.

Such modifications may be employed as are within the scope of the invention.

Having fully described my invention, what I now claim as new, and desire to secure by Letters Patent, is—

1. A hoisting apparatus for pumps, &c., comprising a main supporting-frame, a vibrating frame, an axial support for said vibrating frame on the main supporting-frame, a cable-winding wheel independently mounted on said axial support, power-energized reciprocating means actuating said vibrating frame, separate pawls on the main supporting and vibrating frames and ratchet-

- teeth on said winding-wheel adapted to be engaged by said pawls.
2. A hoisting apparatus for pumps, &c., comprising a main supporting-frame, a vibrating frame, an axial support for said vibrating frame on the main supporting-frame, a cable-winding wheel or drum independently mounted on said axial support, a pawl on the vibrating frame, ratchet-teeth on the winding-wheel adapted to be engaged by said pawl and yielding pressure-imparting means to the said pawl on the vibrating frame.
3. In a hoisting apparatus for pumps, &c., a cable-winding wheel, a supporting-frame therefor, means for imparting rotary motion to said wheel and alternately-acting wheel-retarding devices on said supporting-frame connected with each other.
4. The combination with the main frame, of the hoisting-wheel, an axial support therefor on said frame, ratchet-teeth on said wheel, a vibrating frame independently mounted on said axial support, a pawl on said vibrating frame, an arm pivotally connected with the vibrating frame a link connecting said pawl with said arm and a weight on said arm acting by gravity to hold said pawl in or out of engagement with said ratchet-teeth.
5. In a hoisting apparatus for pumps, &c., a cable-winding wheel, a supporting-frame therefor, means for imparting rotary motion to said wheel, a brake-band on said wheel connected at one end with said frame, a sleeve on said frame, and a pawl and an arm on said sleeve said arm being operatively connected with the other end of the brake-band on said cable-winding wheel and a lever operating the pawl and brake-controlling arm.
6. In combination a main supporting-frame, a winding-drum and ratchet-teeth thereon, a sleeve on said frame and a pawl and a brake-controlling arm on said sleeve and a brake and operating means connected with the pawl and brake-arm and acting by gravity to hold the said pawl in engagement with the ratchet-teeth.
7. In a hoisting apparatus a main supporting-frame, a cable-winding wheel, an axial support for said wheel upon said frame, a vibrating frame independently mounted upon said axial support, a cable upon said winding-wheel an enlargement upon said cable, means for imparting power to and vibrating said frame and intermittently-engaging power-transmitting devices on the said vibrating frame engaging with said wheel and adapted to contact with said enlargement on said cable and to be automatically disengaged thereby from the wheel in the downstroke of the vibrating frame.
8. The combination in a hoisting apparatus with a vibrating frame and cable-winding wheel and cable of intermittently-acting wheel-engaging devices on said frame, a pivoted radial arm on the vibrating frame and a weight, and an arm on said weight adapted to be extended past said cable and connecting devices connecting said radial arm with the wheel-engaging devices.
9. A hoisting apparatus comprising a main supporting-frame, a cable-winding wheel, an axial support therefor on said frame, a vibrating frame independently mounted upon said axial wheel-support, wheel-engaging devices on said vibrating frame imparting rotary motion to said wheel, a suspended wheel above said winding-wheel and a cable extending over said wheel and power-energized reciprocating means actuating said vibrating frame.
10. In a hoisting apparatus a main supporting-frame, a cable-winding wheel upon said frame and cable upon said wheel, means for imparting rotary motion to said wheel, and a derrick, means on the derrick for holding down the main supporting-frame, a cable-sheave on the derrick over which said cable extends, a vibrating frame on said supporting-frame and power-actuated reciprocating devices for winding the cable and devices connected with the power-actuated reciprocating devices for taking up the slack.
11. A hoisting apparatus comprising a main supporting-frame, a cable-winding wheel, an axial support upon said frame for said wheel and a vibrating frame upon said axial support and a horizontally-extended portion of said vibrating frame, self-engaging power-transmitting devices upon the said vibrating frame acting to impart rotary motion to said wheel, an elevated cable-supporting sheave, a hoisting-cable on said wheel extending over said sheave, suspended cable-supports upon the vibrating frame and cable-clamping devices on said cable within said supports and reciprocating power, energized devices imparting a circular reciprocating movement to the vibrating frame and a vertical reciprocating movement to the suspended cable-support on the vibrating frame.
12. The combination with the main supporting-frame of a cable-winding wheel mounted on said frame, an axial support for said wheel and hollow journals supporting said wheel mounted on said axial support, a vibrating frame independently mounted upon said hollow journals, means on said vibrating frame imparting rotary motion to said cable-winding wheel and power-energized reciprocating means actuating said vibrating frame.
13. In hoisting mechanism, a main frame, a vibrating frame mounted thereon, means for communicating a reciprocating motion to said frame, a cable-winding wheel independently mounted on said main frame, and means on said vibrating frame for commun- 125 130 135 140 145 150 155 160 165 170 175 180 185 190 195 200 205 210 215 220 225 230 235 240 245 250 255 260 265 270 275 280 285 290 295 300 305 310 cating an intermittent rotary motion to said wheel, in combination with a cable, suspensory devices on said vibrating frame and a cable-protecting tube carried by said suspensory devices.

14. A hoisting apparatus comprising a main supporting-frame, a cable-winding wheel, an axial support for said wheel upon said frame, a vibrating frame independently connected with said axial support, a horizontal extension of said frame extending beyond the periphery of said wheel, an elevated sheave, a cable upon said wheel extending over said sheave, suspensory devices upon said vibrating frame and cable attachments supporting said cable within said suspensory devices, a pawl pivotally connected with the extended portion of said vibrating frame and ratchet-teeth on said wheel, means

for holding the pawl under pressure in engagement with the ratchet-teeth, a brake-band on said wheel connected at one end with said main supporting-frame, a sleeve adapted to be partially rotated and a support therefor upon said main frame, an arm on said sleeve operatively connected with the other end of the brake-band a pawl connected with said sleeve and engaging with the ratchet-teeth on said cable-winding wheel, a lever for removing said pawl from engagement with the ratchet-teeth and applying the brake-band in the same movement and power-conveying reciprocating means actuating the vibrating frame.

WALTER S. SUTTON.
